UNITED STATES PATENT OFFICE.

HARRY R. DECKER, OF HOUSTON, TEXAS.

AEROPLANE.

1,057,225.

Specification of Letters Patent. Patented Mar. 25, 1913.

Application filed April 3, 1911. Serial No. 618,665.

To all whom it may concern:

Be it known that I, HARRY R. DECKER, a citizen of the United States, residing at Houston, in the county of Harris and State 5 of Texas, have invented certain new and useful Improvements in Aeroplanes, of which the following is a specification.

My invention relates to new and useful improvements in aeroplanes and has more 10 particular relation to the motor and propelling mechanism therefor.

The object of the invention is to provide a device of the character described equipped with an engine of the type known in the art 15 of engine construction as the Gnome engine, and which is bodily rotatable, relative to the supporting frame therefor, and whose cylinders are so arranged as to radiate from a common center, and are provided with wings 20 or blades which serve as lifting, or as driving propellers, the function of said blades depending upon the position of the engine in the frame of the aeroplane. If the plane of rotation of the engine is horizontal the 25 cylinder blades are disposed so as to perform the function of lifting propellers and if the said plane of rotation is vertical the said blades serve as driving propellers, the complete engine serving, in either case, the purpose 30 of a gyroscope to stabilize the machine and prevent the same from capsizing.

With the above and other objects in view my invention has particular relation to certain novel features of construction, operation 35 and arrangement of parts, an example of which is given in this specification and illustrated in the accompanying drawings, wherein:—

Figure 1 is a plan view of the engine 40 showing the radiating cylinders and their appendant wings or blades. Fig. 2 is a side elevation thereof showing the propeller shaft and the propeller carried thereby, said engine and propeller being shown in the relation they will sustain to each other when the engine is mounted to rotate in a plane 45 which is vertical, relative to the frame of the aeroplane. Fig. 3 is a side elevation of an aeroplane showing the motor mounted 50 therein so as to rotate in a horizontal plane and operatively connected with the propeller of the machine, the plane and certain other appendants of the machine, not being shown.

Referring now more particularly to the 55 drawings, the numeral 1 refers to the main

frame of the aeroplane which is supported, when not in air, upon the runners 2.

The numeral 3 refers to the motor or engine, which is constructed after the type of the engine well known in the art, and commonly known to those familiar with engine construction as the Gnome type of engine. The cylinders 4 of this engine radiate from a common center and the complete engine is mounted so as to rotate bodily, relative to 60 its support, the engine rotating in the direction indicated by the arrows in the figures. Each cylinder carries a wing or blade 5, which is an extension thereof and is preferably integral therewith. This blade forms 65 a wing like extension from said cylinder and inclines from the cylinder, at an angle relative to the plane of rotation of the cylinders, each blade extending from its respective cylinders in the same relative direction as the 70 other blades and at the same angle relative to said plane of rotation, and also forming a cutting edge to lessen the resistance of the cylinder with the air. It is readily obvious 75 that as the engine rotates these blades will 80 serve as propellers in the same manner as the ordinary propeller blades, and if the engine is mounted so as to rotate in a horizontal plane and so that the blades will have 85 an upward inclination to the plane of rotation, the said blades will perform the function of lifting propellers and will enable the machine to rise from the ground much more readily than would be the case were the lifting power thereof dependent entirely upon 90 the inclination of the plane, as is the case with aeroplanes now in common use, and it is further obvious that the machine will be more readily sustained in air with an engine 95 of this construction than it would be if dependent entirely upon its plane as a support. It is further obvious that if said engine is mounted so as to rotate in a vertical plane and so arranged that the blades will have a forward inclination relative to the plane of 100 rotation said blades will perform the function of a driving propeller and assist in driving the machine forwardly through the air.

In case the machine is so mounted as to 105 serve as a lifting propeller its drive shaft 6 should be provided with a rigidly mounted bevel gear 7 arranged to mesh with the bevel gear 8 rigidly mounted on the propeller shaft 9 which carries the propeller 10, the 110

cylinder wings 5 serving to assist in lifting the machine and the propeller 10 driving the same forward. If the engine is mounted so as to rotate in a vertical plane its drive shaft 6 may also serve as the propeller shaft. The wings 5 serving to assist the propeller 10 in driving the machine forward. However the engine may be mounted it will serve as a gyroscope and tend to maintain the equilibrium of the machine and prevent the same from capsizing, thus performing the function of a stabilizer.

What I claim is:

- 15 1. In a device of the character described the combination with an aeroplane frame, of a motor carried thereby and bodily rotatable relative thereto, a plurality of cylinders carried by the motor and radiating therefrom, lengthwise blades carried by the cylinders and extending laterally therefrom at an angle of inclination to the plane of cylinder

rotation, and a propeller rotatably mounted upon said frame and having operative connection with the motor.

2. In a device of the character described, 25 the combination with an aeroplane frame, of a motor carried thereby and bodily rotatable relative thereto, a plurality of cylinders carried by the motor, and radiating therefrom, lengthwise blades carried by the cylinders 30 and extending laterally therefrom, and a propeller rotatably mounted on said frame and having an operative connection with the motor.

In testimony whereof I have signed my 35 name to this specification in the presence of two subscribing witnesses.

HARRY R. DECKER.
